(57) **CLAIM**

The ornamental design for a user interface faceplate as shown and described.

DESCRIPTION

FIG. 1 is a front view of a user interface faceplate according to a first embodiment, showing my new design;

FIG. 2 is a top front perspective view thereof in a first environment;

FIG. 3 is a bottom front perspective view thereof in a first environment;

FIG. 4 is a front view thereof in a first environment;

FIG. 5 is a top front perspective view thereof in a second environment;

FIG. 6 is a bottom front perspective view thereof in a second environment;

FIG. 7 is a front view thereof in a second environment;

FIG. 8 is a top front perspective view thereof in a third environment;

FIG. 9 is a bottom front perspective view thereof in a third environment; and

FIG. 10 is a front view thereof in a third environment.

FIG. 11 is a front view of a user interface faceplate according to a second embodiment, showing my new design;

FIG. 12 is a top front perspective view thereof in a first environment;

FIG. 13 is a bottom front perspective view thereof in a first environment;

FIG. 14 is a front view thereof in a first environment;

FIG. 15 is a top front perspective view thereof in a second environment;

FIG. 16 is a bottom front perspective view thereof in a second environment;

FIG. 17 is a front view thereof in a second environment;

FIG. 18 is a top front perspective view thereof in a third environment;

FIG. 19 is a bottom front perspective view thereof in a third environment; and,

FIG. 20 is a front view thereof in a third environment.

In FIG. 1, the outer broken line depicts an environment within which a present user interface faceplate is disposed.

In FIG. 11, the outer broken line depicts an environment within which a present user interface faceplate is disposed.

In FIGS. 1-20, the broken lines depict portions of the article and/or environments that form no part of the claimed design.

In FIGS. 11-20, the left portion of the user interface faceplate is represented with a black color while the right portion of the user interface faceplate is represented with an orange color.

1 Claim, 20 Drawing Sheets
